UNITED STATES PATENT OFFICE.

JULES LINDAUER, OF PARIS, FRANCE.

CORSET.

No. 923,361.

Specification of Letters Patent.

Patented June 1, 1909.

Application filed February 3, 1909. Serial No. 475,871.

To all whom it may concern:

Be it known that I, JULES LINDAUER, citizen of France, residing at 42 Rue du Faubourg du Temple, Paris, in the Republic of France, have invented new and useful Improvements in Corsets, of which the following is a specification.

This invention relates to improvements in corsets.

10 Many ladies prefer corsets to be long at the lower part. The rigid whale bone part of long corsets can be prolonged much lower at the back and sides of the corset than at the front of the same because a very long 15 busk is uncomfortable for sitting. But if the rigid part in front does not completely cover the abdomen, the stomach is driven forward by the compression produced by the tightening of the lace and in order to 20 prevent this inconvenience, it is necessary that below the busk an abdominal belt or other arrangement is provided which can conveniently support the abdomen. It is easy to obtain this result by extending the 25 fabric of the corset below the busk while stopping the whale bones above this extension and to fasten this extension by means of buckles, hooks and eyes, buttons, straps etc., but by the employment of such means 30 an excessive pressure is exerted on the abdomen of a seated woman which causes un- 35 comfortableness at once, and which besides has the very great inconvenience that the eyes or hooks by the excessive pressure that 40 they produce when the woman is seated are apt to tear the fabric of the corset near 45 where they are placed.

In my previous patent No 873,443 dated December 10, 1907 I describe a corset which 40 is provided with suspender carrying tabs having free edges and arranged obliquely on the stomach and attachable to the stockings, together with straight suspenders (the oblique suspenders and the straight suspend- 45 ers each carry the half of the clasp and are attached together on the stocking). This corset provides a perfect means for the closure of the abdominal non rigid part of the corset, below the busk and forms an 50 excellent sustainer for the abdomen; this invention has given excellent results. However for the fixing of the suspender to the stocking and for the adjustment of the suspender to the desired length,—whether the 55 adjustment is made (by shortening or by

lengthening the suspender) by means of a pressure buckle or the like,—or in the absence of any buckle by shortening or by simply lengthening the elastic fabric of the suspender, there are certain difficulties inherent 60 to the principle of suspenders with four branches as in order that the oblique elastic branch which carries the button and which comes beneath the straight elastic branch which carries the clip which is fixed on the 65 button over the stocking can simultaneously exercise an even traction on the corset and on the stocking an excessive minute regulation of each branch to the desired length is necessary. Also even after this minute adjustment the fixation one on the other with interposition of the stockings, of these two parts each carried by a separated branch is less comfortable than if the clip and the button were carried by a single elastic rib- 70 bon. On the other hand if regulating buckles are employed to lengthen or shorten the suspenders to the desired length it is necessary that these regulating buckles be of very small size which lessens their resistance 75 and the adjustment can only be exercised on a very short length without the four buckles at the front rubbing against one another, making a clicking noise and hooking one into another during walking. 80

The present invention has for its object a new arrangement which permits to retain all the useful effects of my former hereinbefore mentioned invention while suppressing the various inconveniences mentioned 90 above.

In the annexed drawing there is shown a form of construction of the improved corset.

Figure 1 shows the corset before the attachment of the suspenders on the stocking. Fig. 2 shows the corset with the suspenders 95 attached.

The corset has in front, below and a little in front of the busk two tabs with free or unattached edges *a a'* arranged obliquely. 100 On each of these tabs there is preferably attached by sewing and by preference at the extremity of each tab an elastic ribbon *b* or *b'* in which is inserted in a manner to be able to freely slide, the complete clasp *c* or *c'* 105 which grips the stocking. This elastic ribbon which is preferably woven so that the front and the back are alike, carries at its extremity a hook *d* or *d'* (or a clasp, button or a device of any kind) allowing to fix this 110

extremity by preference in such a way that it can lightly pivot on a ring f or f' (eyelet buckle or any other appropriate means of attachment) in which it is inserted as soon as the busk is closed; this ring or analogous device f or f' is carried by the half of the corset, opposed to that on which is first fixed the elastic which should hook on it and the elastic ribbon to attach itself to the said ring f or f' which fixes it then to two sides of the corset, is folded once on itself; the slide of the clasp or clip c or c' comes to the bottom of the fold of the ribbon. The ring or analogous device f or f' is carried either by a second straight tab p or p' forming an extension of the corset a little behind the oblique tab of the same side. This straight tab can be made of the material of the corset, if it is considered superfluous to add a tab, the corsets being sometimes sufficiently long at the side of the oblique tab to not require extending. The device f or f' can still be fixed on the rigid part itself of the corset. The oblique tabs by the traction of each suspender which are arranged in a V and form a return on the opposed side of the corset by being fixed to the stocking in the usual manner, automatically sustain the stomach of the woman standing and automatically relax when the woman is seated.

With the improved arrangement the fixing of the clips which hold the stocking is made in a more normal and rational fashion. Further the length of the suspenders can be regulated with the greatest facility by means of a single slide q for each suspender and finally the application of oblique tabs on the abdomen taking place with only a slight traction of the suspender, owing to the sliding of the clip, the stockings only have to resist slight tension and tear less than formerly while being prevented from turning on the leg.

Having now described my invention, what

I claim as new and desire to secure by Letters Patent is:

1. In a corset comprising suspender carrying tabs a a' placed obliquely and crossing one another on the abdomen, the combination of elastic ribbons of adjustable lengths b b' attached respectively by one end to the free ends of said tabs,—clasping devices d d' attached respectively to the other ends of the elastic ribbons, fastening devices f f' carried respectively by the two halves of the corset and each of which is adapted to engage the clasping device of the elastic ribbon carried by the opposite half of the corset and clasp couplers c c' adapted to grip the stockings and slidably engaged respectively with the elastic ribbons, substantially as described and for the purpose set forth.

2. In a corset comprising suspender carrying tabs a a' placed obliquely and crossing one another on the abdomen and straight suspender carrying tabs p p' the combination of elastic ribbons of adjustable length b b' attached respectively by one end to the free ends of said tabs,—clasping devices d d' attached respectively to the other ends of the elastic ribbons,—fastening devices f f' carried respectively by the free ends of the straight tabs p p' and each of which is adapted to engage the clasping device of the elastic ribbon carried by the opposite half of the corset, and clasp couplers c c' adapted to grip the stockings and slidably engaged respectively with the elastic ribbons, substantially as described and for the purpose set forth.

In testimony whereof I have signed my name to this specification in the presence of two subscribing witnesses.

JULES LINDAUER.
